[57] **CLAIM**

The ornamental design for the combined bench and cabinet for housing a swimming pool cover mechanism, as shown and described.

DESCRIPTION

In the drawings:

FIG. 1 is a front perspective view showing a new design for a combined bench and cabinet for housing a swimming pool cover mechanism,

FIG. 2 is a side elevation of the combined bench and cabinet shown in FIG. 1,

FIG. 3 is an enlarged top plan view of the combined bench and cabinet shown in FIG. 1 with a central portion being cut away for reasons of clarity,

FIG. 4 is a front elevation of the combined bench and cabinet shown in FIG. 1 with the central repeating portion cut away for reasons of clarity,

FIG. 5 is an enlarged fragmentary rear view showing one end of the combined bench and cabinet for housing a swimming pool cover mechanism,

FIG. 6 is a cross sectional view of the combined bench and cabinet of FIG. 1 taken along line 6—6.
